CLAIM

The ornamental design for a watch, as shown and described.

DESCRIPTION

FIG. 1 is a front view of a watch thereof;

FIG. 2 is a first end view of a watch thereof;

FIG. 3 is a first side view of a watch thereof;

FIG. 4 is a back view of a watch thereof;

FIG. 5 is a second side view of a watch thereof;

FIG. 6 is a perspective view of a watch thereof; and,

FIG. 7 is a second end view of a watch thereof.

The broken lines in FIGS. 4 and 6 are used to show portions of the watch that do not form part of the claimed design.

1 Claim, 1 Drawing Sheet

FIG. 1

FIG. 2

FIG. 3

FIG. 4

FIG. 5

FIG. 6

FIG. 7
